CLAIM

The ornamental design for a turf roll carousel as shown.

DESCRIPTION

FIG. 1 is a perspective view of the turf roll carousel; FIG. 2 is a left-side view of the turf roll carousel; FIG. 3 is a right-side view of the turf roll carousel; FIG. 4 is a front view of the turf roll carousel; FIG. 5 is a back view of the turf roll carousel; FIG. 6 is a top view of the turf roll carousel; and, FIG. 7 is a bottom view of the turf roll carousel. The broken lines in the drawings illustrate portions of the Turf Roll Carousel that form no part of the claimed design.

1 Claim, 6 Drawing Sheets
